ERNST W. KOPKE AND LOUIS J. STRUEBIG, OF ST. LOUIS, MISSOURI, ASSIGNORS TO
FULTON IRON WORKS COMPANY, OF ST. LOUIS, MISSOURI, A CORPORATION OF
DELAWARE

CANE MILL

Application filed April 17, 1929. Serial No. 355,743.

This invention relates generally to cane mills, and more specifically to improved housings for cane mills, the predominant object of the invention being to provide housings of this type which include as parts thereof roller bearings for supporting the rolls of the cane mills.

Another important object of the invention relates to the provision of cane mill housings of improved construction whereby certain disadvantages inherent in the housings heretofore employed in building cane mills are eliminated.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. 1 is an elevation of a cane mill provided with our improved housings, portions of the rolls of the mills at the center of said mill being broken away to conserve space.

Fig. 2 is a side elevation of the cane mill illustrated in Fig. 1.

Fig. 3 is a vertical section on line 3—3 of Fig. 1.

Fig. 4 is a vertical section on line 4—4 of Fig. 1.

Fig. 5 is a vertical section on line 5—5 of Fig. 2.

Fig. 6 is a section on line 6—6 of Fig. 2.

Fig. 7 is a section on line 7—7 of Fig. 3.

Fig. 8 is a sectional detail showing the means for attaching certain rods to the disks associated with the turnbeam.

Persons familiar with the art to which this invention relates understand the term "housing" when used with reference to cane mills to mean the side frames or supporting elements which rotatably support the rolls of the cane mills at the opposite ends of said rolls. A housing unit is provided with journal boxes for the rolls of the cane mill, and

frequently includes a hydraulic top cap which serves as a means for applying hydraulic pressure to the rolls of the mill.

Prior to this invention the usual design of mill housing included ordinary journal boxes of common and well known construction for supporting the rolls of the mill; that is to say, the housings previously employed were not provided with anti-friction bearings of the roller bearing or ball bearing types. Also, these earlier housings included transverse bolts that resisted the lateral pressures exerted against the side rolls because of the application to the rolls of the mill of the hydraulic load. The housing units disclosed herein include roller bearings or similar anti-friction bearing elements for supporting the rolls of the mills whereby the friction incident to the rotation of the rolls is very materially reduced, and also in the present invention the transverse bolts referred to above are eliminated.

Referring now to the drawings, A designates a cane mill provided with housings constructed in accordance with this invention, said housings being designated generally by the reference character B and the rolls of the mill A being designated by the reference character C. The rolls C are constructed in the manner common to rolls of this type, said rolls each having journal portions C' at their opposite ends of reduced diameter which are known as roll necks.

By referring to Fig. 1 of the drawings, it will be noted that each mill includes a pair of spaced housings B between which the crushing portions of the rolls C are disposed, the roll necks C' at the opposite ends of the rolls being extended through the housings B, and crown wheels D, which are arranged in meshing engagement with each other, being mounted on the roll necks whereby rotary motion will be transmitted from one to another of said rolls.

Considering now the details of construction, the housings B, it will be noted by referring to Figs. 2, 3, and 4 that each housing B when viewed in side elevation tapers from a certain width at the top of the housing to a substantially greater width at the bottom

or base of the housing. The construction of each of the housings B includes vertically disposed wall elements, from which the transverse webs, which are combined with said vertical wall elements to provide a unitary structure, are extended, and by referring particularly to Fig. 3 it will be noted that the housing illustrated therein is provided with a vertically disposed recess 1, which is provided at its lower end with an arcuate seat 2. At the upper edge of the arcuate seat 2 and at opposite sides thereof, the housing is provided with shoulders 3, said shoulders being located in horizontal alignment with the radial center of the arcuate seat 2 as shown in Fig. 3. Above the shoulders 3 the recess 1 provides a guideway for a member 4 which serves as a bearing box for the top roll and is provided with an arcuate face 5 at its lower end, said member 4 being seated on the shoulders 3 so that the arcuate face 5 thereof combines with the arcuate seat 2 to provide a circular wall. The member 4 is capable of vertical movement within the recess 1, the opposite side faces of said member contacting with lining elements 6 arranged in contact with the opposite walls of said guideway. Seated in a recess provided at the top of the member 4 is a plate 7 having an arcuate seat 8 formed therein at its top face, and 9 designates a plunger provided with a curved lower face which is seated in the arcuate seat 8 of the plate 7. The plunger 9 constitutes a part of a hydraulic ram 10 which is located within a chamber 11 formed in the cap 12, said chamber being closed by a closure element 13 secured in place at the upper end of the chamber.

The cap 12 functions as a closure element for the top portion of the guideway 1, said cap having outwardly extended portions 14 provided with inclined top faces 15 which are extended into recesses 16 formed in the opposite side walls of the guideway 1. The recesses 16 are each provided with an inclined top wall with which the top wall 15 of the associated portion 14 contacts. The outwardly extended portions 14 extend transversely of the housing B, and bolts 17 (Figs. 1, 2, and 4) are extended through said portions and through adjacent portions of the housing, whereby the cap 12 is securely fixed to the housing, and the portions of said housing at opposite sides of the guideway 1 are rigidly tied together.

Formed in each of the housings B at opposite sides thereof are downwardly and inwardly inclined recesses 18, each of said recesses at the inner end thereof being closed by an arcuate wall 19, and being open at its outer end at an inclined wall of the housing. At the lower wall thereof each of the inclined recesses is provided with a face 20, and at the inner end of said face said recess

is provided with a shoulder 21 (Fig. 3). The arcuate rear wall of each of the recesses 18 is provided with a pad or lug 22, which is extended transversely of the housing. At the top of each recess 18 the upper wall thereof is provided with an inwardly curved portion 23, which gives to the recess slightly greater height at the inner end thereof, and at said inner end of each recess 18 the top and rear walls of the recess are provided with arcuate shoulders 24, as shown in Fig. 3.

Arranged within the opening provided between the arcuate seat 2 of each of the housings B and the arcuate face 5 of the associated bearing box 4, is a roller bearing 25, which comprises a circular bearing housing 26 and annular members 27 and 28, which provide a raceway in which anti-friction rollers 29 are positioned. The top roll C of the cane mill A is supported for rotation by the roller bearing 25, the journals or necks C' of said top roll at the opposite ends thereof being extended through the raceway members 28 associated with oppositely disposed mill housings B, and said members 28 being securely fixed to said roll journals or necks so that the roll journals and raceway members will rotate as a unit. The bearing housing 26 is provided with a projection 26' which extends into a recess 31 formed in the bearing box 4 so as to prevent rotation of said bearing housing. By referring particularly to Fig. 5 of the drawings it will be noted that the outer face of the bearing housing 26 is curved in a direction transversely of said bearing housing as indicated by the reference character 25', and that the faces of the housing and member 4 with which said curved face contacts are correspondingly curved. The result of this arrangement is that the bearing housing is capable of transverse movement within certain limits with respect to the housing by which said bearing housing is supported, hence universal adaptation of the roller bearing 25 for misalignment of the top roll due to irregularities of feed is allowed. In other words, the substantially spherical form of the top roll roller bearing housing provides universal adaptability to compensate for irregularities in floating, and in the use of our improved structure we obtain a full distribution of the bearing characteristics, regardless of any misalignments due to irregularities of feed. In the case of the usual type of bearing, the load centers are shifted either inwardly or outwardly due to the lack of flexibility or adaptability of the top bearing, which is mounted only for vertical sliding and not for tilting characteristics, as in the use of our invention.

Referring now to the lower rolls, these rolls are also mounted for rotation in roller bearings, the roller bearings for supporting said lower rolls being disposed within the recesses 18 of the housings B, as shown in

Fig. 3. Each roller bearing associated with the lower rolls of the mill comprises a bearing housing 32 provided with a circular upper portion and flat face 33 at the bottom thereof. The flat face referred to contacts with the face 20 of the lower wall of the associated recess 18, and each bearing housing 32 is provided with a face 34 which contacts with the shoulder 21 within the recess. Also, each bearing housing 32 is provided with a flat face 35 arranged to contact with one of the pads 22 which have already been referred to herein.

Within each of the bearing housings 32 a pair of annular members 36 and 37 is arranged, which provide a raceway, and arranged in said raceway is a plurality of anti-friction rollers 38. The journals or necks of the lower rolls at opposite ends thereof are extended through the annular members 37 of the roller bearings, and said annular members are fixed to said journals or necks so that the rolls and the annular members of the bearings will rotate as a unit. Also, the housing 32 of each roller bearing is provided with forwardly extended portions 39, the lower faces of which contact with the lower wall of the associated recess 18 as shown in Fig. 3.

Extended across the open end of each of the recesses 18 is a link 40, said link having a bifurcated lower end portion as shown in Fig. 1. The upper end portion of each link 40 is extended into a recess 41 formed in the associated mill housing B, and the lower bifurcated end of said link straddles an upwardly extended projection 42 formed on said mill housing. At the upper and lower end thereof each link 40 is connected to the associated mill housing B in the manner and by the means illustrated in Fig. 7, said means comprising a pair of oppositely disposed conical members 43 arranged in conical openings formed by bushings 43' in the links and mill housing and provided with aligned longitudinally arranged openings 44 formed therethrough. 45 designates a rod which is extended through the aligned openings referred to, said rod having an enlarged portion 45' at its approximate center and being provided with screw-threaded opposite ends of reduced diameter. A shoulder 46 disposed within the opening formed through each of the conical members 43 and 47 designates a washer, which is forced into contact with shoulder nut 46 by a nut 48 mounted on the adjacent screw-threaded end of the rod 45. On inspection of Fig. 7 it will be plain that in the event any looseness develops in the connection between the links 40 and the portions of the mill housings to which said links are attached, such looseness may be eliminated by merely screwing the nuts 48 inwardly on the screw-threaded ends of the rod 45. This will cause the conical members 43 to be moved toward each other, whereby the increasing diameter of

the inwardly moving conical members will provide close contact between the conical members and the walls of the conical openings in which said conical members are disposed. The bushings are preferably formed of bronze or other non-corrosive material, so as to prevent "freezing" of the conical members resulting from the effect thereon of acid. While Fig. 7 illustrates only the lower end of a link 40, the means for connecting the upper ends of the links to the mill housing is constructed in a similar manner to the means illustrated in Fig. 7, hence it is not thought to be necessary to illustrate in detail the upper portions of one of the links. The enlarged portions 45' at the centers of the rods 45 serve as means to loosen the conical members 43, as by removing the nuts at the ends of the rods 45 and tapping the end of said rod the portion 45' will contact with the end of the conical member toward which said portion is moved, whereby continued tapping on the rod will displace said conical member. Arranged on each of the links 40 is a lug 40^a which is adapted to contact with a lug 40^b in the housing of the associated roller bearing, whereby tilting or outward movement of said roller bearing is prevented.

Referring now to Fig. 4, 50 designates a turnbeam which extends across the mill immediately beneath the top roll of the mill. Fixed to the turnbeam at the top thereof is a trash knife 51, the means for securing the trash knife to the turnbeam comprising a plurality of bolts 52 which extend through the turnbeam, as shown in Fig. 4. The trash knife 51 prevents the trash, i. e., small particles of cane, from dropping with the juice which flows downwardly on the periphery of the roll with which the nose portion of the trash knife contacts. The mass of cane passing over the trash knife is subjected somewhat to the pressure of the top roll of the mill, and this downward pressure is transmitted to the turnbeam 50. The turnbeam is thus subjected to downward pressure, and it must be properly constructed and supported to withstand such pressure. For this reason the turnbeam is a relatively heavy casting, and its ends preferably rest upon pivot members 53, each of said pivot members being extended from a base 54 supported by a projection from the housing. The turnbeam is rockably secured to the pivot members by U-bolts 55, and the turnbeam thus may be turned on the pivots to move the trash knife 51 toward and away from the mill roll with which it is associated.

The means for adjusting the turnbeam comprises horizontal pins or shafts 56 at the opposite ends of said turnbeam, each of said pins or shafts being supported for rotary movement in openings in the walls of the mill housings and being provided with an eccentrically arranged extension 57 formed

on an end thereof which is projected into an elongated, vertically disposed recess 58 formed in the turnbeam at the adjacent end thereof. Fixed to each pin or shaft 56 at the end thereof opposite to the end at which the eccentric extension 57 is arranged is a disk 59 provided with a circular row of apertures 60. The disk 59 has fixed to it at one side thereof a vertically disposed rod 61, said rod 61 and disk 59 being pivotally connected by a pivot pin, which extends through apertures in the legs of the bifurcated upper end of the rod and through one of the apertures formed through the disk. The rod 61 is extended through an aperture formed in a lug 62 on the mill housing (Fig. 2), and at the lower end of the rod 62 same has a pair of nuts and a washer 63 mounted thereon. Interposed between the lug 62 and the washer 63 is an expandable coil spring 64 which tends to move the rod 62 downwardly. At the side of the disk 59 opposite to that side thereof at which the rod 61 is positioned is a similar rod 65. This rod 65 is pivotally attached to the disk 59 by means of a pin which extends through apertures in the rod and an aperture in the disk. The rod 65 passes through an aperture in a lug 66 formed on the housing and is provided at its lower end with nut and a washer 67, and interposed between said washer and said lug 66 is a collar 68.

The coil spring 64 tends to move the rod 61 downwardly and thus the eccentric extension 57 on the rod 56 causes the nose portion of the turnplate to be maintained in close contact with the associated roll of the mill, whereby trash will be scraped from the mill roll referred to. The rod 65 and associated parts tend to steady the turnplate in a manner to prevent vibration thereof.

By referring to Fig. 8 it will be noted that the pins 70 by which the rods 61 are attached to the disk 59 are each provided with a central portion 71 of increased diameter, whereby shoulders 72 and 73 are provided on said pin. Also, the apertures in the legs of the bifurcated upper portions of the rods 61 and 65 are of greater diameter than the associated pins 70. To insert the pins 70 in position where they attach the rods to the disk, said rods are arranged in such positions that the apertures formed through the legs of the bifurcated portions thereof are aligned horizontally with the disk apertures through which the pins 70 are to be extended. The pins 70 are then arranged in place in said aligned apertures, and thereafter the rods 61 and 65 are moved downwardly until the tops of the walls of the apertures in the legs of said rods contact with the tops of the portions of the pins at the opposite ends thereof. When the parts are so positioned the inner faces of the legs of the rods will contact with the shoulders 72 and 73 on the pins, whereby said

pins are prevented from moving longitudinally to escape from the apertures.

Referring to the links 40 of our improved housing, it will be noted that the spaces between the legs of the bifurcated lower ends of said links are of such height that a passageway 75 is provided between the wall 40' of each link 40 and the top face of the portion 42 of the housing to which the lower end of the link is attached (Fig. 3). This space 75 serves as a passageway for shims, which it may be desired to introduce between the faces 20 of the inclined recesses 18 and the bottom faces of the housings of the roller bearings 32 for the purpose of adjusting the mill rolls supported by said roller bearings upwardly. The curved ends thereof provide additional space within the recesses whereby upward adjustment of the roller bearings 32 is permitted. In order to provide for upward movement of the lower rolls so that shims may be arranged within the recesses 18, we form outwardly extended lugs 76 on the outer faces of the housings B (Fig. 4). A suitable jack is interposed between the lugs 76 and the roll necks, and said jack operated to elevate the rolls sufficiently to permit insertion of the shims. In the case of our improved housing the pressure angle, or the angle of relationship between the bottom rolls and the top roll, is always maintained unchanged under all required roll adjustments, and this is contrary to general practice in connection with the use of mill housings employed heretofore. The main advantage in this connection is that the turnplate width and setting is not disturbed to the same degree or in the same manner as has heretofore been the case.

A feature of this invention which is of extreme importance resides in the fact that we eliminate transverse bolts, side caps, jack screws or wedges, and adjusting bolts by maintaining a constant pressure angle at all settings through which all forces are directed along the hypotenuse of the angle to the base of the housing. The bases of the side roller bearing housings rest on planed surfaces approximately 90° to the pressure angle hypotenuse, thereby eliminating the customary horizontal thrust common to other designs. Horizontal alignment of the rolls is assured through the planed surfaces referred to above, and any outward rolling of the roll is prevented by the extended portions 39 on the roller bearing housings which also rest on the angular roller bearing rest surfaces.

It will be noted that the replacing of rolls and bearings has been made a very simple task because of the construction of our improved housing. The completed assembly of the roller bearing units are placed on the roll journals, and by removal of the top cap or side links, the entire roll including the crown wheels and bearings may be dropped into place or removed in a like manner.

Forming a part of each assembled roller bearing unit is a lock ring 77 which screws into the roller bearing shell and closes the raceway thereof. Adjustable ring glands 78 and 79 retain ring packings 78' and 79' at each end of the bearing assembly, thus preventing the loss of lubricant from the roller chamber and excluding the entry of juices or foreign matter. For locking the roller races 10 in position, two sleeves are provided, the inner sleeve 80 being retained by a shoulder 81 on the roll shaft, and the outer sleeve 82 being retained in fixed position by contact with a crown wheel.

15 The value of the application of roller bearings to roll journals of a sugar mill is very apparent. The saving in horsepower under load due to friction is very substantial. In addition, lubricating troubles are reduced to 20 a minimum since the grease reservoirs formed in the roller cages maintain a constant supply of lubricant. As stated above, these reservoirs are sealed against lubricant leakage and contamination by cane juices or other 25 foreign matter from the outside. By preventing juice from entering the lubricant of the journal, we not only prevent its contamination but preclude the corrosive action of juice acids on the shaft journals. Juice 30 guards to prevent cane juices from fouling the lubrication of the journals are unnecessary, and the entire water cooling system for cooling the journals of the rolls is likewise rendered unnecessary.

35 We claim:

1. A housing for a crushing mill comprising a supporting element provided with a pair of recesses arranged to receive the bearings of the lower rolls of the mill, said recesses being inclined inwardly and downwardly with respect to the housing, and being open at their outer ends at walls of said housing, and links extended across the open ends of said recesses, said links being connected at their opposite ends to portions of the housing at opposite sides of the recesses, and each of said links being provided with a rectangular passageway formed therethrough through which shims may be introduced into the associated recess to adjust the position of the bearing therein.

2. A housing for a crushing mill comprising a supporting element provided with a pair of recesses arranged to receive the bearings of the lower rolls of the mill, said recesses being inclined inwardly and downwardly with respect to the housing, and being open at their outer ends at walls of said housing, and links extended across the open ends of said recesses, said links being connected at their opposite ends to portions of the housing at opposite sides of the recesses, said links being each provided with a bifurcated portion of greater length than the portion of the housing which is embraced by

said bifurcated portion, whereby a space is provided between the inner end of the bifurcated portion and the associated housing portion through which bearing adjusting elements may be introduced into the associated 70 recess.

In testimony that we claim the foregoing we hereunto affix our signatures.

ERNST W. KOPKE. 75
LOUIS J. STRUEBIG.
